DESIGN FOR A RUG

Gerard J. Kluyskens, New York, N. Y.

Application January 25, 1937, Serial No. 67,282

Term of patent 3½ years

To all whom it may concern:

Be it known that I, Gerard J. Kluyskens, a citizen of the United States, residing at New York city, county and State of New York, have invented a new, original, and ornamental Design for a Rug, of which the following is a specification, reference being had to the accompanying drawing, forming part thereof, wherein

The figure is a plan view of one-half of the rug showing my new design, the unshown half being similar to the half that is reproduced except for the omission of the floral design.

I claim:

The ornamental design for a rug substantially as shown and described.

G. KLUYSKENS.
